(57) **CLAIM**

The ornamental design for a batch bread slice, as shown and described.

DESCRIPTION

FIG. 1 is front view of a batch bread slice according to a first embodiment of the present invention, the rear view being a mirror image thereof.

FIG. 2 is a top view of the batch bread slice depicted in FIG. 1.

FIG. 3 is a bottom view of the batch bread slice depicted in FIG. 1.

FIG. 4 is a right side view of the batch bread slice depicted in FIG. 1, the left side view being a mirror image thereof.

FIG. 5 is a perspective front, bottom and left side view of the batch bread slice depicted in FIG. 1.

FIG. 6 is front view of a batch bread slice according to a second embodiment of the present invention, the rear view being a mirror image thereof.

FIG. 7 is a top view of the batch bread slice depicted in FIG. 6.

FIG. 8 is a bottom view of the batch bread slice depicted in FIG. 6.

FIG. 9 is a right side view of the batch bread slice depicted in FIG. 6, the left side view being a mirror image thereof.

FIG. 10 is a perspective front, bottom and left side view of the batch bread slice depicted in FIG. 6.

FIG. 11 is front view of a batch bread slice according to a third embodiment of the present invention, the rear view being a mirror image thereof.

FIG. 12 is a top view of the batch bread slice depicted in FIG. 11.

FIG. 13 is a bottom view of the batch bread slice depicted in FIG. 11.

FIG. 14 is a right side view of the batch bread slice depicted in FIG. 11, the left side view being a mirror image thereof; and,

FIG. 15 is a perspective front, bottom and left side view of the batch bread slice depicted in FIG. 11.
